UNITED STATES PATENT OFFICE.

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA.

COOLER ESPECIALLY ADAPTED FOR CANNING.

Application filed February 23, 1921. Serial No. 447,308.

To all whom it may concern:

Be it known that I, ALBERT R. THOMPSON, a citizen of the United States, residing at San Jose, in the county of Santa Clara and 5 State of California, have invented certain new and useful Improvements in Coolers Especially Adapted for Canning, of which the following is a specification.

My invention relates to the class of coolers used in the canning art, for reducing the 10 temperature of canned goods immediately after the "cooking" operation. The necessity for such cooling is now well known and needs no explanation ~~in~~ so far as general 15 requirements are concerned; but, while my present invention is applicable to any situation which calls for cooling, it will be of advantage to point out conditions which render the invention particularly adapted 20 for and essential to coolers which are under a pressure above atmospheric in order to prevent injurious relief from the pressure to which they are subjected in the process 25 of cooking. Accepted practice favors the cooking under pressure above atmospheric. To transfer the cans from a pressure cooker into a cooler at atmospheric pressure is found to be injurious, in that the sudden relief tends to burst the cans or to open their 30 seams. To avoid this the cans should be cooled while under a pressure also above atmospheric, so that there will be no such injurious relief. As, in practice, the cooling 35 medium used is water, it is available to impose the necessary pressure in the cooling chamber by means of a volume of compressed air admitted to said chamber. The cooling medium obviously will rise in temperature as the heated cans from the cooker 40 pass through it; and, as it, therefore, becomes necessary to reduce this temperature the simplest way is to admit cooler water. But as this will increase the water content 45 of the cooling chamber, some means must be provided to withdraw a volume of the heated water equal to the increment of cooler water added. And, finally, such regulation of the volume and temperature of the cooling medium must be under the condition of 50 maintaining the air pressure in the chamber.

With these conditions and objects in view, my invention consists in the novel cooler which I shall hereinafter fully describe by

reference to the accompanying drawings, in 55 which—

Fig. 1 is a side elevation, broken and partly in section, of my cooler.

Fig. 2 is a top plan view of the same at the can-receiving end thereof. 60

Fig. 3 is a vertical cross section, enlarged, of the water volume regulating float-chamber.

1 is the shell, box or tank of the cooler, having a pressure tight can inlet and a pressure tight can exit, and a can-path within it adapted for advancing the can procession through the shell from the inlet to the exit. These are features which may assume various forms and with the details of which 70 my present invention is not concerned. I have accordingly illustrated them in a general way, the inlet being indicated by a pressure tight valve at 2, the exit by a pressure tight valve at 3 and the can advancing path 75 by the fixed helically disposed rail 4, and the annular series of rails 5 carried by a reel 6 rotated by a shaft 7. These parts are driven by suitable mechanism, which for the purpose of illustration, I have shown as 80 comprising a drive shaft 8 with pulley 9, gears 10 to drive a counter shaft 11 which, through gearing indicated by 12 drives the shaft 12' of the inlet and exit valves at 2 and 3 and the reel shaft 7, all as shown in 85 Fig. 1.

Within the cooler chamber is the cooling medium, namely a body of water indicated by 13. This is supplied by a perforated pipe 14 in the bottom of the chamber, said 90 pipe being fed by a supply pipe 15 under the general manual control of a cock 16 and connected with a source of water under pressure, not shown.

Pressure within the chamber of the cooler 95 is provided by compressed air admitted to the top of said chamber by a pipe 17 from a pump indicated at 18. A gauge 19 shows the air pressure imposed.

In the water supply pipe 15 is interposed 100 a regulating valve 20 of some form or type adapted for automatic operation under temperature control.

For this purpose, I have indicated exteriorly a common form of diaphragm operated valve controlled by a compressed air pipe 21, which is itself under the control of a connection 22 from a source of compressed

air indicated at 23. This compressed air connection is under the control of a thermostat 24 exposed to the water in the cooler chamber, Fig. 1.

5 Outside of the cooler shell is a float chamber 25 connected at its lower portion with the water body in the chamber of the shell by a pipe 26, controlled by a cock 27, and at its upper portion with the air pressure space 10 in said chamber by a pipe 28, controlled by a cock 29, so that in said float chamber the water-level is the same as in the cooled chamber, and the air pressure is also the same. From the bottom of the float chamber 15 issues a water discharge pipe 30, which is controlled by any suitable form of float operated valve. For illustration I have shown in Fig. 3 this valve structure as comprising a pair of valves 31 seated in a fitting 32, and having a stem 33 connected by a link 34 with a shaft 35 which is rocked by a lever 36.

Within said float chamber 25 is a float 37, having a stem 38, which is connected with 25 lever 36. The float chamber 25 is sufficiently independent of the cooler tank 1 to enable it to be initially adjusted in elevation to conform to a predetermined level of the water content in the tank. For this purpose I have indicated the pipe connections 30 26 and 28 as provided with suitable elbow joints 39 to provide for their yielding by turning movement to enable the float chamber 40 to be set higher or lower. 40 is a manually controlled outlet from the upper portion 35 of the water body.

The operation is as follows: As before stated, the heated cans pass in procession through the water in the cooler. Though 40 the cans may come from any source, the usual source is the cooker, and, the usual cooker is a pressure cooker, in which case the cooler is a pressure cooler. The cooker and the cooler may be separate shells or they 45 may be cooking and cooling effects in compartments of the same shell. In the present illustration we may assume the cans to come from a pressure cooker and to be delivered without relief from pressure to the cooler 50 through its inlet 2. When the temperature of the water in the cooler, due to the presence of the heated cans, rises above a predetermined degree, the thermostat 24 opens the air pressure connections 22 and 21 so 55 that the compressed air from the source 23 opens the regulating valve 20 and admits colder water from the supply pipe 15, to the cooler, through the perforated pipe 14, it being understood that the water pressure in 60 the supply pipe 15 exceeds the air pressure in the cooler. This increment of cooler water has the two fold effect of reducing the temperature in the water body 13 of the cooler, and by increasing its volume, of raising 65 its level. This latter result has the ef-

fect of lifting the float 37, which through its connections opens the discharge valve 31 from the float chamber 25 and allows the warmer water from the upper portion of the water body to pass out through the discharge pipe 30 without, however, exposing the confined air to said discharge.

Thus not only is the water body cooled by the entrance of the cooler water increment, but also by the discharge of the warmer 75 water. As soon as the temperature of the water body is reduced to the required degree the thermostat reverses its previous function and closes off the water feed; and, as soon as the level of the water body is restored by the discharge through pipe 30, the descended float closes the discharge valve 31 and normal conditions again prevail, the pressure in the cooler not having been released at any time.

I claim:—

1. A cooler especially adapted for canning, comprising a shell containing a cooling medium; means for supplying said medium; said shell having a can inlet and a can exit; 90 means within the shell for conveying the cans through the cooling medium from the inlet to the exit; means for regulating the supply; a thermostat exposed to the medium within the shell, for controlling said supply-regulating means; means for discharging said cooling medium from the shell; and means dependent upon a predetermined volume of said medium within the shell to control the discharge therefrom.

2. A cooler especially adapted for canning, comprising a shell containing a cooling medium said shell having a can inlet and a can exit; means within the shell for conveying the cans through the cooling medium 105 from the inlet to the exit; means for replenishing said medium by admission to its lower levels; means for regulating the replenishing supply; a thermostat exposed to the medium within the shell for controlling said replenishing-supply-regulating means; means for discharging a modicum from the upper levels of said cooling medium in the shell; and means dependent upon a predetermined volume of said medium within the 110 shell to control the discharge.

3. A cooler especially adapted for canning, comprising a shell containing a cooling medium said shell having a can inlet and a can exit; means within the shell for conveying the cans through the cooling medium from the inlet to the exit; means for supplying said medium; means for regulating the supply; means for establishing and maintaining within said shell a pressure above 120 atmospheric; a thermostat exposed to the medium within the shell, for controlling said supply-regulating means; means for discharging said cooling medium from the shell without release of internal pressure; and 130

means dependent upon a predetermined volume of said medium within the shell to control the discharge therefrom.

4. A cooler especially adapted for canning, comprising a shell containing a cooling medium said shell having a can inlet and a can exit; means within the shell for conveying the cans through the cooling medium from the inlet to the exit; means for replenishing said medium by admission to its lower levels; means for regulating the replenishing supply; means for establishing and maintaining within said shell a pressure above atmospheric; a thermostat exposed to the medium within the shell for controlling said replenishing-supply-regulating means; means for discharging a modicum of said cooling medium from its upper levels without release of internal pressure; and means dependent upon a predetermined volume of said medium within the shell to control the discharge therefrom.

5. A cooler especially adapted for canning, comprising a shell containing a cooling liquid said shell having a can inlet and a can exit; means within the shell for conveying the cans through the cooling liquid from the inlet to the exit; means for replenishing said liquid by admission to its lower levels; a valve for regulating the replenishing supply; means for establishing and maintaining within said shell a fluid pressure above atmospheric; a thermostat exposed to the liquid in the shell, and connections therefrom to control the replenishing valve; a float chamber having a communication with the liquid in the shell and with the fluid pressure therein; a discharge pipe from said float chamber disposed to draw from the upper levels of the cooling liquid; a valve to control said discharge pipe; and a float in the float chamber, with connections to operate said discharge valve.

6. A cooler especially adapted for canning, comprising a shell containing a cooling liquid said shell having a can inlet and a can exit; means within the shell for conveying the cans through the cooling liquid from the inlet to the exit; means for replenishing said liquid by admission to its lower levels; means for regulating the replenishing supply; a thermostat exposed to the liquid within the shell for controlling said replenishing supply-regulating means; a vertically adjustable float chamber associated with said shell and communicating with the liquid therein; a discharge pipe from said float chamber disposed to draw from the upper levels of the cooling liquid; a valve to control said discharge pipe and a float in the float chamber with connections to operate said discharge valve.

7. A cooler especially adapted for canning, comprising a shell containing a cool-

ing liquid said shell having a can inlet and a can exit; means within the shell for conveying the cans through the cooling liquid from the inlet to the exit; means for replenishing said liquid by admission to its lower levels; a valve for regulating the replenishing supply; means for establishing and maintaining within said shell a fluid pressure above atmospheric; a thermostat exposed to the liquid in the shell, and connections therefrom to control the replenishing valve; a vertically adjustable float chamber having a communication with the liquid in the shell and with the fluid pressure therein; a discharge pipe from said float chamber disposed to draw from the upper levels of the cooling liquid; a valve to control said discharge pipe; and a float in the float chamber, with connections to operate said discharge valve.

8. A cooler especially adapted for canning, comprising a shell containing a cooling medium said shell having a can inlet and a can exit; means within the shell for conveying the cans through the cooling medium from the inlet to the exit; means for establishing and maintaining in said shell a pressure above atmospheric; means for supplying said medium with fresh cool increment; and means for withdrawing, without release of pressure within the shell, a portion of said medium equal in volume to that of said increment.

9. A cooler especially adapted for canning, comprising a shell containing a cooling liquid said shell having a can inlet and a can exit; means within the shell for conveying the cans through the cooling liquid from the inlet to the exit; means for establishing and maintaining in said shell an air pressure on said liquid above atmospheric; means for adding a fresh cool increment to said liquid; and means for withdrawing, without release of air-pressure within the shell, a portion of said liquid equal in volume to that of said increment.

10. A cooler especially adapted for canning, comprising a shell containing a cooling liquid said shell having a can inlet and a can exit; means within the shell for conveying the cans through the cooling liquid from the inlet to the exit; means for establishing and maintaining in said shell an air pressure on said liquid above atmospheric; means for supplying to the lower levels of said liquid an increment of fresh cool liquid; and means for withdrawing from the upper levels of said liquid, without release of air-pressure within the shell, a portion of said liquid equal in volume to that of said increment.

In testimony whereof I have signed my name to this specification.

ALBERT R. THOMPSON.
